UNITED STATES PATENT OFFICE.

MAURICE ROBBINS, OF BOSTON, MASSACHUSETTS.

COLLAR.

Application filed December 13, 1927. Serial No 239,732.

My present invention has reference to shirts that are provided with attached turnover or turn-down collars, and my object is to secure the collar to the shirt in a manner 5 that will prevent the wrinkling thereof and hold the collar in proper position even after long wear, and further wherein the collar is provided with reinforcing means that afford a guide for the tie, so that the tie can 10 not only be readily passed through the fold of the collar but when tied will assume its proper position with respect to the collar.

To the attainment of the foregoing and other objects which will present themselves 15 as the nature of the invention is better understood, the improvement consists in certain other novel features of construction, combination and operative association of parts, one satisfactory embodiment of which 20 is disclosed by the accompanying drawings.

In the drawings:

Figure 1 is a perspective view of the improvement.

Figure 2 is a horizontal sectional view 25 through the collar.

Figure 3 is a sectional view approximately on the line 3-3 of Figure 2.

Figure 4 is an inner face view of the neck portion of the shirt to which the collar is 30 attached.

Figure 5 is a fragmentary view similar to Figure 4 illustrating a modification.

Figure 6 is a similar view illustrating a further modification.

Figure 7 is a similar view illustrating a 35 still further modification.

With my improvement the shirt 1 need not be provided with the usual neck band, as the collar, formed from the same material

40 as the shirt, has its inner fold and a portion of its outer fold stitched directly to the neck portion 2 of the shirt. As disclosed by the

drawings, the collar is of the usual fold type, the inner fold of which, in Figures 1, 2 and 45 3 of the drawings, is indicated by the numeral 3 and the outer fold by the numeral 4.

The inner fold 3 has its lower edge stitched throughout its length to the neck portion 2 of the shirt and the outer fold 4

50 has its lower edge stitched to both the portion 2 and to the front of the shirt. This line of stitching is for distinction indicated by the numeral 5. By stitching the edge of the outer fold of the collar to the shirt and

55 likewise by stitching the inner fold to the neck portion of the shirt neither fold of the

collar is liable to wrinkle and will, therefore, retain its normal shape even after the shirt and collar have been worn a comparatively long time. However, I brace or reinforce the collar with respect to the shirt by 60 additional means as will now be described.

Before the outer fold of the collar is stitched to the shirt or preferably before either of the folds are stitched to the shirt 65

I stitch to the inner fold or face 3 of the collar, at points adjacent to its outer edge, tabs 6. These reinforcing tabs are preferably in

the nature of triangular strips and the lower and pointed edges thereof are stitched, as 70

at 7, to the shirt, the line of stitching 5, at the pointed and confronting ends of the collar passing through the end tabs 6. The tabs 6 in addition to forming bracing or

reinforcing means for the collar also serve 75 as guide means for the strap portion 8 of a necktie. The inner face or fold 3 of the collar is extended beyond the confronting edges of the outer face or fold thereof and terminates in a line with the pleated and lapping

front portion of the shirt. For distinction 80 these extending portions are indicated by the numerals 9 and 10, and the said portions are

provided one with a button and the other with a button hole or both with button holes 85 for the reception of a removable button. Both the portions 9 and 10, directly inward

of the confronting ends of the outer face of the collar are formed with openings 11 and 12, respectively, and, of course, there is a

line of stitching around these openings to reinforce the same. The strap 8 of the necktie passes through the openings 11 and 12 so

that the outer strands of the tie may be 90 knotted, as at 13, in the usual manner.

In Figure 5 the construction is similar to that described, except that the tabs 14 have substantially rectangular body portions and

their lower edges are substantially V-shaped and these edges are stitched to the shirt.

In Figure 6 a tab 15, substantially semi-cylindrical in plan is provided with a button hole to receive a button 16 therethrough and

which button is stitched to a shirt, while in Figure 7 the tab 17 is of substantially rectangular formation. In all instances it is to

be understood that the tabs are suitably spaced so that the strap of the necktie can be readily inserted between the tabs and the inner face or fold of the collar.

The construction and advantages of my improvement will, it is thought be under-

stood and appreciated by those skilled in the art when the foregoing description has been carefully read in connection with the accompanying drawings so that further detailed description will not be required.

Having described the invention, I claim:

A garment comprising a shirt having a fold collar around the neck portion thereof, the inner fold of the collar having its lower edge stitched to the neck portion of the shirt, and the outer fold of the collar having its lower edge stitched to both the neck portion and front of the shirt, the inner fold, at the

open front of the collar having extending portions which are designed to be connected 15 and which have openings therethrough inward of the confronting ends of the outer fold for the passage of the band of a necktie, and stiffening and reinforcing tabs 20 stitched to the inner fold of the collar and to the inner face of the shirt below the neck portion thereof and between which tabs and the inner fold of the collar the strap of the necktie is guided.

In testimony whereof I affix my signature.

MAURICE ROBBINS.
